UNITED STATES PATENT OFFICE

HARRY R. McMAHON, OF CORAOPOLIS, PENNSYLVANIA

BUMPER END CONSTRUCTION

Application filed May 7, 1931. Serial No. 535,642.

This invention relates to a bumper end construction and more particularly to such a construction as will provide smoothly operating parts under all conditions, even 5 when very tightly assembled.

In certain types of bumpers the front or impact bar or bars is or are not disposed vertically, but on the contrary may be slightly inclined. In such a construction the use of 10 the usual rear bar found in present constructions does not take into account the pitch or inclination of said bar or bars and hence when the assemblies are tightened the parts bind so that upon impact excessive wear and 15 even breakage too frequently occurs, or at best, the binding prevents the proper and intended functioning of the respective portions, so as in effect to provide a rigid unyielding bumper, which is highly undesirable.

20 One of the objects of the present invention is the provision of a bumper end construction which obviates the above and other defects and disadvantages and which additionally has advantages peculiar to its own construction.

25 A further object is to provide a bumper end construction of the type wherein inclined or non-vertical bar ends may be used but a construction which, nevertheless, has a normal pivoting action without the accompaniment of undesirable binding which ordinarily occurs in constructions not provided with the present invention.

30 A still further object resides in providing 35 the indicated construction with a rear bar of a modified type which inhibits any binding action, but on the contrary permits the desired relative pivotal movement of the parts.

40 Other and further objects and advantages will be understood by those skilled in this particular field.

45 In the accompanying drawings, I have illustrated certain desirable ways of carrying out the present invention wherein:

Fig. 1 is an edgewise elevational view of an assembled bumper end construction with the impact bars and the rear bar shown in section.

50 Fig. 1a is a view at right angles to Fig. 1.

Fig. 2 is a plan view of Fig. 1 with certain portions omitted.

Fig. 3 is a fragmentary view similar to Fig. 1 of a modified form of the invention.

Fig. 4 is a view of the invention applied 55 to a different type of bumper construction, as a single bar bumper; and

Fig. 5 is a view of Fig. 4 in plan with certain parts omitted, analogous to Fig. 2.

Similar numerals refer to corresponding 60 parts throughout the several views.

In Figs. 1, 1a and 2, I have shown my invention in connection with a bumper construction having a plurality of impact bars 10 the ends of which may be slightly or somewhat inclined from the vertical (see Fig. 1a), the lower portion of the upper bar end and the upper portion of the lower bar end being more inwardly located than the upper portion of the upper bar end and the lower portion of the lower bar end, respectively. In other words, the axes of the bar ends are so inclined, to the desired degree, that they are non-vertical and slope toward the terminal of the rear bar. The lower portion of the 70 top bar 10 and the upper portion of the lower bar 10 is each cut away at its inner side portion to form cutouts or slots 11, of the shape shown, in the generally barrel-shaped portions 12 which result from bending the ends 75 of the impact bars around into substantial contact with their own rear surfaces.

Rear bar 13 has its terminal bent around to form an eye or a cylinder 14 and instead of the rear bar extending tangentially from 85 said cylindrical portion as is the case in constructions other than my own, the rear bar extends from the central portion of the cylindrical portion, that is, in line with the center, as is very clearly shown in Fig. 2, for 90 example. This rear bar 13 is so disposed that its cylindrical portion 14 is partially inserted in the barrel-shaped terminals 12 of the impact bars 10 and the vertical shoulders 15 formed by the edges of the slots 11 form a 95 limiting stop for the pivotal movement of the rear bar and at the same time the opposing slots form in effect a horizontal guide-way in which said rear bar, in pivoting, operates. A suitable bolt 16 passes through the 100

barrel-shaped terminals of the impact bars and also through the interposed cylindrical portion 14 of the rear bar, thus pivotally associating said parts in operative assembly. 5 The bolt is provided with a suitably enlarged head 17 which rests upon the flange of a suitable washer member 18, thus enclosing the top of the construction and the bottom of the bolt is provided with a nut 20 which holds in 10 place the washer member 19 which serves to close the bottom of the construction, thus forming a practically entirely enclosed construction. While not so shown, I may, of course, provide a suitable lock washer between the nut 20 and washer member 19.

As shown in Fig. 3, the slots 11' in the bar-shaped terminals 12 may be substantially U-shaped, thus providing in effect vertical shoulders 15' to act as stops at each end of 20 the pivotal movement of the rear bar, the length of the slots being variable and designed to permit the desired degree of movement between the parts depending upon the particular bumper involved. The presence of portions of metal 21 also provides a somewhat stronger and more enclosed construction.

In Figs. 4 and 5, I have applied the same principle to bumpers of the single bar type. 30 In these figures it will be noted that the single impact bar 22 has a barrel-shaped terminal 23 and a slot 24 horizontally disposed about centrally of the height of the bar through which passes the end 25 of the rear bar 26, said end being bent into a cylindrical portion, as shown, from which the rear bar extends centrally and not tangentially. It will be understood, therefore, that when such an assembly is tightened the forces will 40 be straight line centered forces and so distributed that there will be no tendency to bind the parts or to so position them as to prevent the desired pivotal movement between such parts.

This is in complete contradistinction to the prior art devices which bind or jam worse the tighter the assembly, but in the present construction due to the peculiar relationship of the parts there is no binding tendency, but 50 the parts can be tightened as much as possible or desired without disturbing the capacity of the parts to move or pivot relatively under abnormal conditions, such as when an impact occurs.

I do not intend that the above shall be precisely limited to that shown, but the same may be adapted wherever the principles herein involved are encountered. While I have shown the impact bars of Fig. 1 as being 60 plano-convex I am not, of course, limited to such a construction nor am I limited to a concavo-convex bar as shown in Fig. 4. Whatever the cross-sectional configuration of the bars, they may be utilized in connection with the present invention provided that their ends

are somewhat inclined from the true vertical in which latter event my invention finds most usefulness.

While I have shown only one end construction, this is for simplicity and convenience 70 and the other end construction is identical thereto, except, of course, that it is of opposite "hand".

The slot of Fig. 4 may extend to the end of the material of the terminal as in Fig. 1, 75 and the rear bar, while narrower preferably than the front bar, may be wider than the slot, in which case a construction similar to that of an application to Harry E. Figgie, Serial No. 535,629, filed May 7, 1931, may be 80 utilized.

What I claim as new and desire to secure by Letters Patent is:

1. In a bumper construction, a plurality of impact bars having their ends inclined from the vertical and having terminal portions, a rear bar having a terminal portion interposed between the terminal portions of the impact bars, the rear bar extending centrally from its terminal, and means for pivotally securing said members in operative assembly. 85

2. In a bumper construction, a plurality of impact bars having their ends inclined from the vertical and having terminal portions, a rear bar having a terminal portion interposed between the terminal portions of the impact bars from which the rear bar extends centrally, and means for pivotally securing said members in operative assembly, 95 the terminal portion of said rear bar being cylindrical and fitting partly within each of the terminals of the impact bars.

3. In a bumper construction, a plurality of impact bars having their ends inclined from the vertical and having barrel-shaped terminal portions, a rear bar having a terminal interposed between the terminals of the impact bars from which said rear bar extends centrally, said barrel-shaped terminals having slots for guiding and limiting the movement of said rear bar, and means for pivotally connecting said members in operative assembly. 105

4. In a bumper construction, a plurality of impact bars having their ends inclined from the vertical and having barrel-shaped terminal portions, a rear bar having a terminal interposed between the terminals of the impact bars from which said rear bar extends centrally, said barrel-shaped terminals having slots for guiding and limiting the movement of said rear bar, and means for pivotally connecting said members in operative assembly, 110 said rear bar terminal being cylindrical. 120

5. In a bumper construction, a pair of impact bars, having their ends inclined from the vertical, said bars also having their ends bent around to form barrel-shaped terminals 130

provided with oppositely disposed horizontal slots, a rear bar having a cylindrical terminal disposed partly within the barrel-shaped terminals of said impact bars and from which 5 said rear bar extends centrally, said slots guiding and limiting the movement of said rear bar and means for pivotally connecting said members in operative assembly free from binding action.

10 6. In a bumper construction, a pair of impact bars, having their ends inclined from the vertical, said bars also having their ends bent around to form barrel-shaped terminals provided with oppositely disposed horizontal 15 slots, a rear bar having a cylindrical terminal disposed partly within the barrel-shaped terminals of said impact bars and from which said rear bar extends centrally, said slots guiding and limiting the movement of said rear 20 bar and means for pivotally connecting said members in operative assembly free from binding action, said slots being substantially U-shaped.

25 7. In a bumper construction, a plurality of impact bars having their ends inclined from the vertical and having terminal portions each provided with a slot, a rear bar having a terminal portion, interposed between the terminal portions of the impact 30 bars, from which the rear bar extends centrally, and means for pivotally securing said members in operative assembly, the terminal portion of said rear bar being cylindrical and fitting partly within each of the 35 terminals of the impact bars, said slots being substantially U-shaped.

40 8. In a bumper construction, an impact bar having its end inclined from the vertical and bent around to form a barrel-shaped terminal having a horizontally disposed slot therein, a rear bar having a terminal disposed within said barrel-shaped terminal and from which said rear bar extends centrally, said slot guiding and limiting the movement of said rear 45 bar and means for pivotally connecting said rear bar in operative association with said impact bar so as to be free from binding action.

50 9. In a bumper construction, an impact bar having its end bent around to form a barrel-shaped terminal having a horizontally disposed slot therein, a rear bar having a terminal disposed within said barrel-shaped terminal and from which said rear bar extends centrally, said slot guiding and limiting the 55 movement of said rear bar and means for pivotally connecting said rear bar in operative association with said impact bar so as to be free from binding action, said impact bar end being inclined slightly from the vertical, and 60 said rear bar terminal being cylindrical.

65 10. In a bumper construction, a plurality of impact bars having their ends inclined from the vertical and having barrel-shaped terminal portions, a rear bar having a terminal interposed between the terminals of

the impact bars from which said rear bar extends centrally, said barrel-shaped terminals having slots for guiding and limiting the movement of said rear bar, and means for pivotally connecting said members in operative assembly, 70 said rear bar terminal being cylindrical, said slot being situated about centrally of the height of said barrel-shaped terminal and optionally extending to the end of said terminal.

75 11. In a bumper construction, a plurality of impact bars, each such bar having its ends bent around to form barrel-shaped terminals, each such terminal having its axis inclined from the vertical, a rear bar having its ends bent around to form cylindrical terminals such that the rear bar extends centrally from its terminals, end constructions being formed from a non-binding pivoting of operatively associated impact and rear bar terminals.

80 12. In a bumper construction, a plurality of impact bars, each such bar having its ends bent around to form barrel-shaped terminals, each such terminal having its axis inclined from the vertical, a rear bar having its ends bent around to form cylindrical terminals such that the rear bar extends centrally from its terminals in effect constituting a continuation of a diameter of said terminals, end constructions being formed from a non-binding 85 pivoting of operatively associated impact and rear bar terminals.

90 In testimony whereof, I have hereunto subscribed my name this 4th day of May, 1931.
